UNITED STATES PATENT OFFICE.

THEODOR KURRELL AND JOSEPH HAAS, OF LOS ANGELES, CALIFORNIA.

DESIGN FOR A MATCH OR TOOTHPICK DISPENSER.

41,214.

Specification for Design.

Patented Mar. 7, 1911.

Application filed August 5, 1910. Serial No. 575,858. Term of patent 7 years.

To all whom it may concern:

Be it known that we, THEODOR KURRELL and JOSEPH HAAS, both subjects of the Emperor of Germany, and both residing at Los Angeles, in the county of Los Angeles and State of California, have invented a new, original, and ornamental Design for a Match or Toothpick Dispenser, of which the following is a specification, reference being had to the accompanying drawing, forming part thereof.

The figure is a perspective view of a match or toothpick dispenser, showing our new design.

We claim:

The ornamental design for a match or toothpick dispenser, as shown.

THEODOR KURRELL.
JOSEPH HAAS.

Witnesses:

CLARENCE J. WILLIAMS,
HARRY A. BROOKS.
